ATTORNEY

UNITED STATES PATENT OFFICE

EUGENE B. BERKOWITZ, OF KANSAS CITY, MISSOURI

SAVINGS BANK ENVELOPE

Application filed October 6, 1930. Serial No. 486,660.

My invention relates to envelopes, and more particularly to a savings bank envelope for containing coins and the like, and has for its principal object to provide a simple and inexpensive savings receptacle into which coins may be readily inserted but which must be defaced or totally destroyed for removal of the coins.

In accomplishing this and other objects of 10 the invention, I have provided improved details of structure, the preferred form of which is illustrated in the accompanying drawing, wherein:

Fig. 1 is a perspective view of a savings 15 bank envelope constructed in accordance with my invention.

Fig. 2 is a longitudinal central sectional view through the envelope illustrating the insertion of a coin.

Fig. 3 is a perspective view of the rear side 20 of the envelope showing the upper and lower flaps torn loose from the side flaps to better illustrate the construction.

Referring more in detail to the drawing: 25 1 designates an envelope of the character described, preferably constructed of a blank consisting of relatively strong paper, and comprising a front body portion 2, preferably rectangular in shape and having integral side flaps 3 and 4 folded laterally over 30 the rear face of the body portion 2. The flaps 3 and 4 overlap, preferably in the center of the body portion 2, and are sealed by an adhesive indicated at 5.

The top and bottom edges of the body portion 2 are provided with relatively short flaps 6 and 7, folded rearwardly over the ends of the side flaps 3 and 4, and are sealed thereto by adhesive indicated at 8 and 9, to form a 35 closed receptacle.

Formed centrally of the body portion of the envelope and preferably adjacent the upper end thereof is a substantially U-shaped slit 10 comprising a horizontal cut 11 substantially equal in length to the diameter of the largest coin that may be inserted in the envelope, and formed at the ends thereof are lateral cuts 12 and 13 to provide a flap or lip 14 for closing the opening bounded by the cuts 11, 12, 13 and the flap 14 when the flap

is moved to open position as upon insertion of a coin, as shown in Fig. 2.

The body portion of the envelope is also preferably provided with a plurality of lines 15, 16 and 17 for receiving the name, address and school of the pupil owning the envelope. A schedule 18 which may be printed below the coin slot preferably includes columns 19 and 20 for amounts of deposits, and columns 21 for totals of the amounts contained in the envelope after successive deposits.

Coins to be deposited in the envelope are pressed against the lip and pushed through the slit. After a coin drops through the slit the inherent tension of the material of which the envelope is formed will cause the lip to close. It will then be relatively impossible to shake the coins back through the opening, rendering it necessary to break the seals of the envelope or to tear the envelope for removal of the coins.

Amounts and totals of deposits may be entered in the proper columns and upon delivery of the envelopes containing the savings to the depository bank entry of the total in the envelope may be made in a corresponding pass book.

What I claim and desire to secure by Letters Patent is:

1. In an envelope of the character described a body portion having a U-shaped slit for forming a coin receiving opening and a flexible integrally formed lip having opposite side faces lying flush with opposite side faces of the body portion for closing the opening.

2. In an envelope of the character described, a body portion having a slit therein forming a coin-receiving opening and an integral flexible lip having opposite side faces lying flush with opposite side faces of the body portion for closing the opening, side flaps integral with the body portion and sealingly engaged with each other, and end flaps sealingly engaged with the side flaps to form a closed envelope.

3. A savings bank comprising a body portion having a U-shaped slit adjacent one end forming a coin-receiving opening, the body portion within said slit forming an integral

flexible lip arranged to lie flush with opposite faces of the body portion for closing said opening, side flaps integral with said body portion and folded so as to overlap across said slit whereby the part of the flaps engaged by a coin inserted through the slit is reinforced by said overlap, means for securing said overlapped portions together, integral end flaps formed on said body portion and adapted to overlap said side flaps, and means for securing said side and end flaps together.

4. In an envelope of the character described, a body portion having a U-shaped slit 15 therein forming a coin-receiving opening, side flaps integral with the body portion and sealingly engaged with each other, and end flaps sealingly engaged with the side flaps to 20 form a closed envelope, said flexible lip being located a greater distance from one of said end flaps than the width of said slit and having its free edge extending toward the opposite end flap.

5. In testimony whereof I affix my signature.
EUGENE B. BERKOWITZ.
